ELEVATOR INTERLOCKING DEVICE.

1,298,948.

Specification of Letters Patent.

Patented Apr. 1, 1919.

Application filed January 13, 1919. Serial No. 270,776.

To all whom it may concern:

Be it known that I, FRANK C. HOLBERG, Jr., a citizen of the United States, residing at Philadelphia, county of Philadelphia, 5 and State of Pennsylvania, have invented a new and useful Improvement in Elevator Interlocking Devices, of which the following is a full, clear, and exact description, reference being had to the accompanying drawings, which form a part of this specification.

The object of my invention is to provide effective interlocking mechanism which will prevent the opening of the gate at each floor closing the elevator shaft except when the 15 car is immediately opposite the landing and which will prevent the car being operated to leave the landing until after the gate is closed. Such mechanism is known in the art, and my more specific object is to 20 simplify the mechanism as far as is consistent with insuring its certain and accurate operation. A further object is to so construct the mechanism that it cannot be tampered with by the elevator attendants so as 25 to render it inoperative.

A preferred embodiment of the invention is shown in the drawings. This preferred construction embodies certain structural features disclosed in an application filed by 30 Thomas W. Jenkins, Serial No. 244,680, filed July 13, 1918, with the omission of the device therein shown for rendering the interlocking mechanism inoperative and with the interlocking mechanism therein shown substantially simplified and improved. I do 35 herein claim as my invention any structural features disclosed in said application.

Figure 1 is a partial face view of the gate closing the shaft and of that portion of the 40 locking mechanism directly coacting therewith.

Fig. 2 is horizontal section showing the locking mechanism in plan on an enlarged scale.

Fig. 3 is a section through part of the car showing in elevation the mechanism for locking the controller.

Fig. 4 is a vertical section on the line 4—4 of Fig. 2.

Figs. 5 and 6 are face views of the part of the locking mechanism shown in Fig. 1 in two other positions respectively.

Fig. 7 is a vertical section on the line 7—7 of Fig. 5.

Fig. 8 is a vertical section on the line 8—8 55 of Fig. 6.

Fig. 9 is an end view of the locking mechanism looking to the left of Fig. 5.

Inside the elevator shaft, at each landing 60 z , a locking plate a carries the locking mechanism for the gate y at that landing. z represents the floor of an elevator car shown as on a level with the landing.

A bar b , secured to the gate y , extends downward over the face of the plate a , 65 where it engages, when the gate is closed or only slightly opened, a notch c' in a locking wheel c . The positions of the bar b and wheel c , when the gate is fully closed, are 70 shown in Fig. 1.

Assuming that the car is not directly opposite the landing, and that it is attempted to open the gate, the wheel c is turned, in clockwise direction, by the bar b , until a lug e on the wheel engages a stop formed by 75 the inside corner of one end of an angle plate f secured to the plate a . At this time the bar b has not cleared the notch in wheel c and therefore the gate is locked from further movement in the direction to open. 80

It will be observed, in Fig. 7, that the wheel c is pushed out, in the direction of its axis, by a spring g , so as to cause the lug e to aline with the stop on plate f . When, however, the gate is fully closed and the 85 wheel c is in the position shown in Fig. 1, a lug h on the wheel c engaging the inner face of the plate f , holds the wheel c in its inner axial position. As the wheel is turned away from this position, the internal cam 90 face 14 of the stop plate f , along which the lug h slides, permits the spring to push the wheel c away from plate a to cause the lug e , when it reaches the plate f , to strike it. In the return movement of the wheel c , the 95 lug h , riding along the cam face 14, pushes the wheel in toward the plate a . If, however, in the clockwise movement of the wheel c away from the position shown in Fig. 1, it is maintained pressed in against the 100 spring g , the lug e will, in its turning movement, clear plate f and move along within its inside face until the lug h on the wheel contacts with a stop i fixed on plate a , as shown in Fig. 6. Before the wheel has 105 reached this position, the bar b will have cleared the notch in wheel c so that the gate may be fully opened.

The wheel *c* is pressed inward against the action of spring *g*, only when a car is directly opposite a landing. The mechanism for so acting upon wheel *c* will now be described.

Pivoted on the plate *i* is a hinged plate *k* having, along its free end, a ridge *m* and feet *n* adapted to be engaged by a cam *j* forming a part of wheel *c*. Assuming that 10 a car is not directly opposite the landing, and that the wheel *c* is turned in the initial gate-opening movement above described, the cam *j* engages the feet *n* and swings the plate *k* out on its pivot until the cam clears 15 the feet *n* and the turning movement of the wheel *c* is arrested by the stop-plate *f* as above described. If, however, the outward swing of the plate *k* be arrested before it has cleared the cam *j*, the wheel *c* will be kept 20 from moving out along its axis, which will allow the turning movement of the wheel *c* to continue and release the bar *b* from engagement therewith to permit the gate to fully open. The outward swinging movement 25 of the plate *k* is so arrested only when a car is directly opposite the landing and by mechanism about to be described. It may be mentioned that while the free end of the plate *k*, when the gate is fully closed, is 30 held in by means of a spring *o* (see Fig. 2), the power of this spring is not sufficient to overcome the spring *g*.

Beneath the floor *z* of the car is an angle frame *p* to which is pivoted a three-armed lever *q*. One of the arms of lever *q* is pivotally connected to a sleeve *r* slidable through the frame *p*. Within the open inner end of this sleeve is inserted a pin *r'* abutting against a vertically extending shoe *s* 35 beveled at opposite ends and backed by a strong tension spring *t*. The shoe *s* is carried by a short arm *s'* which is pivotally mounted on a small bracket *u* secured to the frame *p*. The outward movement of the 40 shoe *s* is limited by an adjustable stop-bolt *v*. A spring *w* between one arm of lever *q* and the frame *p* acts to normally hold the sleeve *r* and shoe *s* outward as far as the stop *v* permits. In this position, when a car 45 is running past, or has just stopped at, a landing, the shoe *s* just clears the ridge *m* of the hinged plate *k*.

When, however, the car has stopped directly opposite a landing, the shoe *s* is 50 immediately opposite the ridge *m*. If now, the gate be opened, the wheel *c* will have turned through but a small arc when the outward movement of the hinged plate *k* (caused by the engagement of the cam *j* 55 with the feet *n*) will be arrested, and during a short further turning movement of the wheel *c* the continued engagement between the cam *j* and the plate *k* will maintain the wheel *c* close to the plate *a*, so that, in the 60 still further movement of the wheel *c* the

lug *e* will clear the plate *f*. As hereinbefore explained, this permits the bar *a* to ride out of the notch in wheel *c* and the gate to be fully opened. It should be stated, at this point, that the spring *t* is an emergency 70 spring, normally inactive, and of substantially greater strength than the spring *g*; also that the spring *w*, although weaker than the spring *t*, plus the weight of the controller locking mechanism hereinafter 75 described, is substantially stronger than the spring *g*. The effect, therefore, of the initial action between cam *j* and hinged plate *k* is necessarily not to displace the shoe *s* but to maintain the wheel *c* close to plate *a*, as described. 80

However, before the cam *j* has cleared the hinged plate *k*, the further action of cam *j* upon hinged plate *k* will be to cause the latter to operate directly upon shoe *s*, to 85 swing the lever *q* on its axis. The lever *q*, through a horizontal rod 10 and a bell crank 11, operates an upright locking rod 12, which is adapted, when the lever *q* is swung as described, to enter a notch in the controller 13 on the car. At the time of this 90 operation, the controller has been brought to the position required to stop the car and it is held locked, by the rod 12, in this position until the gate *y* is returned to its closed 95 position. In the end portion of the closing movement of the gate, the bar *b* returns the wheel *c* to its initial position and spring *w* at once acts to return the lever *q* to its normal position, thereby restoring the parts to 100 the position shown in Figs. 1 and 2 and withdrawing rod 12 from engagement with controller 13.

Thus the locking or latching mechanism 105 described performs the function of an interlock, holding the car from being operated when the gate is opened and locking the gate from opening except when the car is directly opposite the landing.

The construction herein set forth is an improvement upon existing mechanism, in that 110 it is certain in its action, very simple in construction when its certainty of operation is considered, and incapable of being readily tampered with to render it inoperative. One 115 of the serious objections to certain known interlocks, which otherwise possess considerable merit, is the ease with which the interlocking mechanism may be "plugged" (as it is known in the art); that is, rendered inoperative by the elevator attendants. The present construction does not lend itself to 120 this abuse.

While the tension spring *t* may be omitted 125 and the shoe *o* made integral with the sleeve *r*, this is undesirable. It may be that at certain times the controller lock may be removed or otherwise rendered inoperative to permit the car to operate while one of the gates is in an open position for the purpose 130

of making some repair. In these circumstances the shoe *s* will project out into the path of the hinged plate *k* and will be struck thereby when the car presses the open gate.

5 The effect will be to compress the spring *t* until the shoe *s* has been overridden. Otherwise, the car would receive an abrupt check, or, what is more likely, the locking mechanism would be broken by the impact.

10 Having now fully described my invention, what I claim and desire to protect by Letters Patent is:

1. In elevator locking mechanism, the combination with the landing gate, of a 15 turnable member, means on the gate adapted, as the gate is moved from its closed position, to turn the turnable member, and a stop adapted to arrest the turning movement of the turnable member and thereby 20 hold the gate from further opening, said turnable member being movable in the direction of its axis into position to enable it to clear the stop and thereby permit its turning movement to continue until the 25 gate is released.

2. In an elevator locking mechanism, the combination with the landing gate and the car, of a turnable member movable in the direction of its axis, means on the gate 30 adapted, as the gate is moved from its closed position, to turn the turnable member, a stop adapted to arrest the turning movement of the turnable member and thereby hold the gate from further opening, 35 a spring adapted, before the turnable member is engaged by the stop, to move the turnable member along its axis into alinement with the stop, and means carried by the car, and operable when the car reaches a predetermined 40 position, to hold said spring from so operating, thereby enabling the turnable member to clear the stop.

3. In elevator locking mechanism, the combination with the landing gate and a 45 movable car, of a turnable member, means on the gate adapted as the gate is moved from its closed position, to turn the turnable member, a stop adapted to arrest the movement of the turnable member, said 50 turnable member being movable in the direction of its axis into position to enable it to clear the stop, a cam on the turnable member, a swinging member adapted to be actuated by the cam, and a shoe carried by 55 the car adapted, when the car is in a definite vertical position relatively to said gate, to limit the cam-actuated movement of the swinging member, thereby causing the lat-

ter, as the turnable member continues to turn, to maintain the turnable member in 60 position to cause it to clear said stop.

4. In an elevator locking mechanism, the combination with the landing gate, the car, a controller on the car, and a controller lock, of a turnable member, means on the 65 gate adapted, as the gate is moved away from its closed position, to turn the turnable member, a stop for the turnable member, a spring tending to move said turnable member along its axis into alinement with 70 said stop, means carried by the car adapted to restrain said turnable member as it turns from being moved into alinement with said stop by said spring, said car-carried means being also operable by said turnable member 75 to operate said controller lock.

5. In an elevator locking mechanism, the combination with the landing gate and the car, of a turnable member movable in the direction of its axis, means on the gate 80 adapted, as the gate is moved from its closed position, to turn the turnable member, a stop adapted to arrest the turning movement of the turnable member and thereby hold the gate from further opening, 85 a spring adapted to move the turnable member along its axis into alinement with said stop, mechanism carried by the car and operable when the car reaches a predetermined position to hold said spring from so 90 operating, thereby enabling the turnable member to clear the stop, a controller on the car, said mechanism being operable by said turnable member to lock said controller, and a spring adapted to return said mechanism to normal position. 95

6. In an elevator landing mechanism, the combination with the landing gate, the car, a controller on the car, and a controller lock, of a turnable member, means on the 100 gate adapted, as the gate is moved away from its closed position, to turn the turnable member, a stop adapted to arrest the movement of the turnable member, a spring adapted to render said stop operative, mechanism carried by the car and operable, by 105 said turnable member, when the car reaches a predetermined position, to render said controller lock operative and move said turnable member out of operative relation 110 with said stop, and a spring adapted to return said mechanism to normal position.

In testimony of which invention, I have hereunto set my hand, at Philadelphia, Pa., on this 27th day of December, 1918.

FRANK C. HOLBERG, JR.
